DESIGN FOR A DRESS

Elvira Ceisler, New York, N. Y.

Application April 8, 1937, Serial No. 68,623

Term of patent 3½ years

To all whom it may concern:

Be it known that I, Elvira Ceisler, a subject of Hungary, residing in the city, county, and State of New York, have invented a new, original, and ornamental Design for a Dress, of which the following is a specification, reference being had to the accompanying drawing forming part thereof.

Fig. 1 is a front view of a dress showing my new design.

Fig. 2 is a rear view thereof.

The characteristic feature of my design resides in the combination on the dress as shown of contrastingly colored loops having matching inserts serving as pockets and the button theme on the collar and waist line as shown.

I claim:

The ornamental design for a dress, substantially as shown and described.

ELVIRA CEISLER.
